ELECTRON-BEAM DEFLECTION SYSTEM
 Seymour Goldberg, Lexington, and Kenneth J. Germeshausen, Newton Center, Mass., assignors to Edgerton Germeshausen and Grier, Inc., Boston, Mass., a corporation of Massachusetts

Filed Oct. 18, 1957, Ser. No. 690,950

11 Claims. (Cl. 315—18)

The present invention relates to electron-beam deflection apparatus and, more particularly, to cathode-ray deflection systems of the long traveling-wave type.

In copending application, Serial No. 591,339, filed June 14, 1956, for Cathode-Ray Apparatus and Method by Kenneth J. Germeshausen, Seymour Goldberg and Daniel F. McDonald, there is disclosed a traveling-wave deflection apparatus comprising a pair of helical windings formed about insulative spacers semi-circular in cross-section, with the diameter boundaries thereof disposed parallel to and spaced from one another to permit the electron beam or stream of the cathode-ray tube to travel between the windings. By designing the signal velocity along the axis of the windings to equal the electron-beam velocity between the windings, transit-time distortion is eliminated and high deflection sensitivity is attained.

Practical difficulties are encountered, however, in designing the deflection apparatus to attain the above results. In view of the coupling between adjacent turns of the windings, it is, indeed, difficult to obtain a satisfactory signal-transmission characteristic in the winding and there sometimes results a destruction of the high-frequency response characteristics of the deflection windings. In addition, the positions assumed by the pair of windings relative to the grounded conductive cathode-ray housing within which the deflection apparatus may be disposed, are interdependent and these is a decided limitation upon the possible spacing of the windings from one another and hence upon the actual size of the path therebetween available for the electron-beam flow. This, of course, limits the possible deflection range of the apparatus and the electron beam diameter.

An object of the present invention, accordingly, is to provide a new and improved deflection apparatus of the above-described character that shall not be subject to these disadvantages but that shall, on the contrary, provide improved high-frequency response and greater latitude for relative positioning of the deflection windings. In summary, this end is attained through the employment of a pair of flat-oval helical windings, each preferably disposed about a grounded planar conductive sheet. Further details of construction are later presented.

Other and further objects will be explained hereinafter and will be more particularly pointed out in the appended claims.

The invention will now be described in connection with the accompanying drawing of which

FIG. 1 is a perspective view illustrating the invention in preferred form, with parts broken away to show details of construction;

FIG. 2 is cross-sectional view, upon an enlarged scale, taken upon the line 2—2 in FIG. 1, looking along the direction of the arrows; and

FIG. 3 is a schematic longitudinal section of a modification.

A preferably conductive cathode-ray housing, tube or envelope 1 contains therewithin, at one end, an electron gun of any conventional type, such as, for example, of the type disclosed in the said copending application, which is generally indicated by the legend "gun," but is not further illustrated since it forms no part of the details of the present invention and it is not desired to detract

2

from the essential elements of the invention. At the other end, the envelope 1 may be provided with a target or screen, so labelled. The electron beam or stream passing from the gun toward the target or screen, at a velocity determined by the adjustment of the gun voltages, as is well known and as is explained, for example, in the said application, passes between a pair of spaced, coextensive, substantially parallelly oriented deflection windings 3, 3' of the traveling-wave helical type, but constructed in accordance with the present invention.

As before stated, it is desired to equate the deflection signal transit time along the deflection windings 3, 3' to the electron-beam transit time through the space between the windings. Since the electron-gun optics pre-determines the electron velocity, it is therefore necessary to construct the windings 3, 3' to have the required transmission-line characteristics that can effect this equality, and to do so without destroying high-frequency response as a result of the turn-to-turn coupling of the windings. The problem involves, indeed, from the practical point of view, the minimizing of the electrical transit time per turn of the deflection winding while maintaining the required characteristics of the deflection apparatus. This problem is admirably solved in accordance with the invention, with the aid of ground planes inserted within each of the windings to reduce the current coupling between adjacent turns. Preferably, also, the winding itself is wound as close to the ground planes as feasible, in flat-oval fashion thereby to minimize the path length of each turn of the helix. More than this by employing wide ribbon or tape-like windings the spacing between the turns can be kept small. The close winding and ribbon spacing, however, are subject to the limitation that they must produce the required effective transmission-line impedance. The small spacing between adjacent turns, moreover substantially eliminates any effect from the ground plane or the voltage field distribution between helices. This results in maximum sensitivity and minimum distortion. Note that required dimensions, width of tape, spacing to ground plane, pitch etc. can be calculated with good approximation by well known parallel plane transmission line formulas provided turn-to-turn coupling is small.

The ground planes are illustrated as substantially flat conductive plates 5, 5' about which the preferably ribbon or tape windings 3, 3' are closely wound in flat-oval fashion, more clearly evident in FIG. 2. The plates 5, 5' extend beyond the windings at both ends and are there supported within the envelope 1 in fixed position by brackets 7 that may be brazed or otherwise secured to the inner wall of the envelope 1. The ground potential may thus be applied to the plates 5, 5' from the preferably grounded envelope wall 1.

The windings 3, 3' may, in turn, be supported by insulating rods or members 9, 9' running throughout their length and terminating in brackets 11. The ends of the insulating rods 9, 9' pass through the brackets 11 and are secured to the ground-plate brackets 7 as at 13. The windings 3, 3' may thus be mechanically supported by the ground-plate brackets 7 and maintained closely wound about the ground-plane plates 5, 5' but out of electrical contact therewith.

Signal input and output connections may be conveniently and efficiently provided by coaxial-line sections 15, 17, extending outside the envelope 1 with the outer conductors 15 in electrical contact therewith. The inner conductors 17 may pass within the envelope 1 to engage the winding terminal brackets 11, as at 19, which may electrically connect with the ends of the winding.

Not only are the before-mentioned difficulties attendant upon the use of prior-art traveling-wave deflection sys-

tems thus obviated by the present invention, but additional novel results are also obtained. Whereas, as before stated, the positions assumed by the prior-art deflection windings were interdependent and the space available for the electron path therebetween was accordingly limited, the ground-plane plates 5, 5' of the present invention maintain ground symmetry for each winding 3, 3' so that the windings are substantially independent of one another and can be separated any desired distance, thus achieving great flexibility in available electron-deflection space dimensions. More than this, the prior-art deflection apparatus, in view of the interdependence of the positions of the pair of windings, had to be maintained parallel to one another throughout. The present invention, however, permits of variation in the shape of the path defined between the helical windings 3, 3', so that, for example, the windings may diverge somewhat at an end, as shown to the right in FIG. 3, permitting the attainment of improved deflection performance.

If the improved sensibility described in the said copending application is to be obtained, the electron-beam focusing coils or other means F, FIG. 1, may substantially centrally overlap the helical deflection field.

Further modifications will also occur to those skilled in the art, it being understood, for example, that the mechanical supporting structure illustrated and described is but one of many that could be employed to attain the novel results herein described, and all such are considered to fall within the spirit and scope of the invention as defined in the appended claims.

What is claimed is:

1. In a system having a portion connected to ground, an electron-beam deflection apparatus comprising a pair of spaced co-extensive helical windings each wound about, but maintained out of electrical contact with, a conductive ground plate connected to said ground of the system, thereby to maintain ground symmetry for each winding.

2. Electron-beam deflection apparatus comprising a pair of spaced co-extensive helical windings positioned within a conductive envelope and each wound about, but maintained out of electrical contact with, a conductive ground plate connected to the envelope, thereby to maintain ground symmetry for each winding.

3. Electron-beam deflection apparatus comprising a pair of spaced co-extensive helical windings positioned within a conductive envelope and each wound about, but maintained out of electrical contact with, a conductive ground plate connected to the envelope, thereby to maintain ground symmetry for each winding and signal-applying means comprising coaxial-line sections each connected to extend outside the envelope with the outer coaxial conductor connected to the envelope and the inner coaxial conductor passing through the envelope to connect with the helical windings.

4. Electron-beam deflection apparatus comprising a pair of spaced co-extensive helical windings within a conductive envelope, each winding being wound about, but maintained out of electrical contact with, a conductive ground plate, thereby to maintain ground symmetry for each winding, the ground plate having supporting means for holding the plate fixed within and in electrical contact with the envelope, the windings being insulatively and mechanically supported by the plate-supporting means.

5. Electron-beam deflection apparatus comprising a pair of spaced co-extensive helical windings within a conductive envelope, each winding being wound about, but maintained out of electrical contact with, a conductive ground plate, thereby to maintain ground symmetry for each winding, the ground plate having supporting means for holding the plate fixed within and in electrical contact with the envelope, the windings being insulatively and mechanically supported by the plate-supporting means, and signal-applying means comprising coaxial-line sections each connected to extend outside the envelope with

the outer coaxial conductor connected to the envelope and the inner coaxial conductor passing through the envelope to connect with the helical windings.

6. Electron-beam deflection apparatus comprising a pair of spaced co-extensive flat-oval helical windings of substantially flat conductive ribbon within a conductive envelope, each winding being wound closely about, but maintained out of electrical contact with, a conductive ground plate, thereby to maintain ground symmetry for each winding, the ground plate having supporting means for holding the plate fixed within and in electrical contact with the envelope, the windings being insulatively and mechanically supported by the plate-supporting means, and signal-applying means comprising coaxial-line sections each connected to extend outside the envelope with the outer coaxial conductor connected to the envelope and the inner coaxial conductor passing through the envelope to connect with the helical windings.

7. In a system having a portion connected to ground, an electron-beam deflection apparatus comprising a pair of spaced co-extensive helical windings each wound about, but maintained out of electrical contact with, a conductive ground plate connected to said ground of the system, thereby to maintain ground symmetry for each winding, the pair of ground plates and the corresponding windings diverging near an end to improve deflection performance.

8. In a system having a portion connected to ground, an electron-beam deflection apparatus comprising a pair of spaced co-extensive helical windings each wound about, but maintained out of electrical contact with, a conductive ground plate that extends beyond both ends of the winding and that is connected to said ground of the system, thereby to maintain ground symmetry for each winding.

9. Electron-beam deflection apparatus as claimed in claim 4 and in which the plate-supporting means comprises a bracket extending to the envelope wall and the winding supporting means comprises an insulative member extending along the winding and connected with the said bracket.

10. In a system having a portion connected to ground, an electron-beam deflection apparatus comprising a pair of spaced co-extensive helical windings each wound about, but maintained out of electrical contact with, a conductive ground plate connected to said ground of the system, thereby to maintain ground symmetry for each winding, the windings being disposed on opposite sides of the electron beam, with the space between the ground plate and the inner surface of the winding free of impedance discontinuities.

11. In a system having a portion connected to ground, an electron-beam deflection apparatus comprising a pair of spaced coextensive conductive ground plates disposed within an envelope, helical winding means wound about at least one of the ground plates but maintained out of electrical contact therewith, means for applying electron-beam deflection current to said winding means, means for connecting both said ground plates to said system ground, and means for projecting an electron beam between the said winding means and the other ground plate.
